INFANT'S SLEEPING AND TETHERING
GARMENT

James P. Whiskeman, Jr., Kirkwood, Mo.

Application March 27, 1946, Serial No. 657,542

6 Claims. (Cl. 128—134)

1

This invention relates to infant's sleeping garments. It has for its principal object to devise a garment of the above type having a tethering strap for holding the infant under the crib covers while permitting the infant to turn over in the crib and allowing freedom of movement of the infant's legs. Other objects are to provide for quickly and easily detachably securing the tethering strap to the foot of the bed; to provide for separably connecting the tethering strap to the garment so that the strap may be detached from the garment and the infant removed from the crib without detaching the strap therefrom and so that the strap will not dangle from the garment when the infant is out of the crib; to prevent accidental detachment of the strap from the garment; and to provide for holding the skirt portion of garments of gown form down at the front and back. The invention consists in the infant's sleeping and tethering garment and in the parts and combinations and arrangements of parts hereinafter described and claimed.

In the accompanying drawing, which forms part of this specification and wherein like symbols refer to like parts wherever they occur,

Fig. 1 is a perspective view of a crib, showing an infant occupant thereof provided with a sleeping and tethering garment embodying my invention,

Fig. 2 is a plan view of said garment,

Fig. 3 is an enlarged fragmentary vertical sectional view on the line 3—3 in Fig. 1,

Fig. 4 is an enlarged fragmentary sectional view on the line 4—4 in Fig. 2,

Fig. 5 is a plan view of a modified form of sleeping and tethering garment; and

Fig. 6 is a fragmentary perspective view of the crotch portion of the bifurcated garment shown in Fig. 5.

The infant's sleeping and tethering garment shown in Figs. 1 to 4, inclusive, of the accompanying drawing comprises an ordinary gown or skirt type garment A and a tethering strap or tape B of cloth or other suitable flexible material. Sewed or otherwise secured to the inner faces of the front and back of the skirt portion of the bed garment or gown A are semi-circular reinforcements 1 of cloth or other suitable material arranged with their straight lower edges flush with the lower edge of said skirt. Each of the reinforcements 1 is provided with one element of a separable fastener, preferably the socket element 2, of an ordinary head-and-socket type snap fastener.

The garment engaging end of the tethering

2

strap or tape B is provided with two head members 3 of the above type of separable fastener, the head portions of said members projecting on opposite sides of said strap and the two members being spaced apart transversely thereof. The other or anchoring end portion of the strap B is also provided with a conventional snap fastener, the two members of said fasteners being spaced apart lengthwise of the strap along the longitudinal center line thereof with the head member 4 projecting from one side of said strap and with the socket member 5 located in the other side thereof.

The tethering strap or tape B is fastened to the foot end of a bedstead or crib C, preferably by passing the anchoring end of said strap around the foot rail D of the crib spring and snapping the socket member 5 into engagement with the head or ball member 3. The free end of the strap B is then secured to the gown B worn by the infant occupant of the crib C by positioning said end between the opposing reinforcing members 1 fixed to the bottom of the skirt at the front and back portions thereof. Each of the two head members 3 carried by said end of said strap is then snapped into one of the two socket members 2 carried by the reinforcing members 1.

In the modified construction shown in Figs. 5 and 6 my invention is shown embodied in a garment A¹ having a bifurcated lower portion. In this construction two overlapping semi-circular flaps 1^a are sewed along their straight edges to the crotch portion of the bifurcated garment A¹ and are each provided on their opposing faces with the snap fastener socket members 2^a that are spaced apart crosswise of said tabs. The tethering strap or tape B is secured to the garment A¹ by placing the garment retaining end of said strap between the two crotch flaps 1^a and snapping each of the head members 3^a of the snap fasteners into one of the socket members 2^a of a flap.

The hereinbefore described infant's sleeping and tethering garment has numerous important advantages. The tethering strap may be quickly and easily anchored at one end to the foot portion of the crib and the other end of said strap may be readily fastened to the garment between the legs of the infant, thereby preventing the infant from climbing out of the covers while, at the same time, permitting the infant to roll sideways in the crib and to have free movement of its legs. The strap may be quickly and easily detached from the garment when it is desired to remove the infant from the crib or to allow the

infant greater freedom of movement therein. When garments of the gown or skirt type are used, the strap serves to hold down the front and back portions of the skirt. The strap engaging portions of the garment serve to reinforce and strengthen the same and to prevent the fasteners from pulling out of these portions; and the transverse spacing of the two snap fasteners at the garment engaging end of the tethering strap or tape serves to prevent accidental disengagement of the snap fasteners.

Obviously, the hereinbefore described sleeping and tethering garment admits of considerable modification without departing from the invention. Therefore, I do not wish to be limited to the precise arrangements shown and described except as limited by the scope of the appended claims.

What I claim is:

1. An infant's sleeping garment of bifurcated form providing a reinforced crotch having a flap with securing means thereon in the crotch portion thereof and a tethering strap adapted to be secured at one end to the foot of a bedstead, and means for securing the other end of said strap to the securing means on the crotch flap of said bifurcated garment.

2. An infant's sleeping garment of bifurcated form having a pair of overlapping front and back flaps in the crotch thereof securing means on said flaps and a tethering strap adapted to be separably attached at one end to the foot of a bedstead, and means for separably securing said other end of said strap to said former securing means between the pair of crotch flaps of said bifurcated garment.

3. The combination set forth in claim 2 wherein said separable securing means comprises two two-part snap fasteners, one part of each of said two-part fasteners being secured to one of said crotch flaps and the cooperating part being mounted on one face of said strap.

4. The combination set forth in claim 2 wherein said separable securing means comprises two head-and-socket type snap fasteners having head

members mounted on opposite sides of said strap and socket members mounted on the opposing faces of said pair of overlapping crotch flaps.

5. An infant's sleeping garment of bifurcated form having a reinforced crotch portion and a tethering strap adapted to be secured at one end to the foot of the bedstead, and means comprising snap-fasteners for detachably securing the other end of said strap to said reinforced crotch portion of said bifurcated garment, thereby providing free movement of the infant's legs.

6. In a child's sleeping garment and restraining device, the combination comprising a sleeping garment having a body covering portion, a pair of leg portions integral with said body portion and extending therefrom, a crotch portion formed between said extended leg portions at the lower end of said body portion, a thin, narrow flexible strap, attaching means for applying said strap to a fixed object, a reinforced area in said crotch portion greater in width than said narrow strap, and fastening means attaching said strap to said reinforced area, said fastening means positioned at the opposite end of said strap from said fixed object applying means whereby a restraining force is exerted on said body portion by said fixed object through said strap and is spread out from said strap through said wider reinforced area.
